(57) **CLAIM**

We claim the ornamental design for a stud removal device, as shown and described.

DESCRIPTION

FIG. 1 is a perspective view from the top of our ornamental design of the stud removal device;

FIG. 2 is a perspective view from the bottom of the stud removal device of FIG. 1;

FIG. 3 is a front elevation view of the stud removal device of FIG. 1;

FIG. 4 is a rear elevation view of the stud removal device of FIG. 1;

FIG. 5 is a side elevation view of the stud removal device of FIG. 1;

FIG. 6 is a top plan view of the stud removal device of FIG. 1; and,

FIG. 7 is a bottom plan view of the stud removal device of FIG. 1.

The broken lines depict portions of the stud remover device in which the design is embodied that are not considered part of the claimed design.
